(57) **CLAIM**

The ornamental design for a batting practice tee, as shown and described.

DESCRIPTION

FIG. 1 is a perspective view of a batting practice tee showing my new design;

FIG. 2 is a front elevation of the batting practice tee as viewed from the lower left in FIG. 1;

FIG. 3 is a rear elevation of the batting practice tee as viewed from the upper right in FIG. 1.

FIG. 4 is a side elevation of the batting practice tee as viewed from the lower right in FIG. 1, the opposite side elevation being a mirror image thereof;

FIG. 5 is a top plan view of the batting practice tee as viewed from the top in FIG. 4.

FIG. 6 is a bottom plan view of the batting practice tee as viewed from the bottom in FIG. 4;

FIG. 7 is a perspective view similar to FIG. 1 but showing the batting practice tee mounting, in broken lines, ball-supporting tube members and storage clips therefor to illustrate the environment of the batting practice tee in one condition for display; and,

FIG. 8 is a perspective view similar to FIG. 7 but showing the batting practice tee mounting, in broken lines, ball-supporting tube members and storage clips therefor to illustrate the environment of the batting practice tee in another condition for display.
